UNITED STATES PATENT OFFICE.

MARK ST. CLAIR ELLIS, OF THE UNITED STATES NAVY.

SELF-SCORING TARGET.

1,131,549.

Specification of Letters Patent.

Patented Mar. 9, 1915.

Application filed January 21, 1911. Serial No. 603,980.

To all whom it may concern:

Be it known that I, MARK ST. CLAIR ELLIS, a citizen of the United States, lieutenant commander of the United States Navy, stationed at the United States Naval Magazine, Mare Island, California, have invented certain new and useful Improvements in Self-Scoring Targets; and I do hereby declare the following to be a full, clear, and exact 10 description of the invention, such as will enable others skilled in the art to which it appertains to make and use the same.

My invention relates to improvements in targets in which marking at the pits by persons is done away with.

My target is an electro-mechanical target adapted for small-arms target practice, and my object is to enable the firer to stand at the firing point and conduct his target practice alone, having the spot which he hits on the target shown up to him on an annunciator which is located conveniently at his side, whereas the target at which the firer aims may be at a great distance from the 25 firing point. Furthermore, the marking will be instantaneous, and the errors in marking introduced by the ordinary methods obviated. I attain these objects by the mechanism illustrated in the accompanying drawings, in which—

Figure 1 shows a front elevation of the target with the annunciator, battery, and cable attached. Fig. 2 shows a vertical central sectional view of an improved adjustable contact maker, Fig. 3 is a detail view of the shuttle and shuttle holder hereinafter referred to and Fig. 4 shows an elevational detail view of a designating plate together with the means employed of securing it to 30 the front shuttleboard bulk-head.

Similar letters refer to similar parts throughout the several views.

Referring to the drawings attached hereto, the invention will be described with reference to its use with the regulation United States Army "A" target.

The action of my target is positive, and consists of the following members, viz: (a) An electrical annunciator shown at "A" in Fig. 1, which I prefer to have constructed in miniature of the target face itself. (b) A battery shown at "B" in Fig. 1, which is preferably of the storage battery type of about 20 volts. (c) A cable "C" extending 50 between the annunciator and the contact makers of the target itself. (d) The target

face "H" shown in Figs. 1 and 2, at which the firer aims, and the electro-mechanical target, details of which are shown in Figs. 2, 3 and 4.

The electro-mechanical features of my invention consists of the following members, reference being had to Fig. 2: "F" is a firm foundation upon which the structure is based, "C" is a bracket or frame for holding the paper target "H." Mounted back of "H" and securely upon the bed-plate "F," is the front holding bulkhead "E," which is preferably made of $\frac{1}{2}$ " steel plate reinforced by distance pieces 7. The 60 object of these distance pieces is to prevent vibration in "E" and to fill in the space between the planes of the Nos. 5 and 3 sections, enabling the same size of spring holder to be used for each and every designating 65 plate if so desired. On this front bulkhead "E" are secured suitable strong springs 6, to which the designating plates "P" are secured. These designating plates "P" are made from hard steel or armor 70 plate, and are cut into segments of the size and shape of the part of the target which they are intended to represent.

The United States Army "A" target as is well known, is divided up into portions 85 having the count of five, four, three and two; the number five count being the center of the target. Mounted in the front bulkhead are the contact shuttle holders 8, secured by the nuts 12 shown in Fig. 3, and 90 the shuttles are held in contact with the rear face of the designating plates "P" by the spring 10. Mounted on the bed-plate "F" in rear of the front bulkhead "E" is the board "D" for holding the adjusting 95 shuttles. This consists of wood or asbestos-board or other suitable material. This shuttle board "D" holds the adjusting contact makers shown in detail in Fig. 3, and in which 13 is a bolt with enlarged head 100 held in battery by the spring 9, and secured to "D" by the holder 14. Adjustment of this contact maker is obtained by means of the nuts 18 which limit the movement of 13 to the front. Also attached to the adjusting 105 shuttles are the wires 15 of the cable "C."

Having thus described the various members, the action of the target is as follows:—The firer at the firing point aims at the paper target "H" and assuming that he 110 hits a portion of said target having a count for example number 5, the projectile will

pass through the paper screen and impinge upon "P" at some point as shown in Fig. 2 on the designating plate numbered 5. This designating plate withstands the projectile, breaking it to pieces, but the blow imparted to the designating plate by the projectile is taken up by the spring 6, and as the front shuttle 11 rests against the rear face of the designating plate number 5, motion will also be imparted to it. It will therefore move backward against the action of the spring 10 and through the shuttle holder 8 until it touches the rear shuttle 13, whereupon the electrical circuit is completed and the annunciator numbered 5 will indicate that a number 5 has been struck. Each segment or designating plate is individually wired to the annunciator, and the common return wire is attached to the front bulkhead "E" so that with any one of the shuttles 11 impinging upon its own adjusting shuttle 13, the electrical circuit is closed and the annunciator indicates the segment struck. The front shuttle 11 not only enables a prolonged electrical contact to be made, but also tends to check vibration in the designating plate upon which it abuts. Arrangement is made for adjustment of the rear shuttle 13 so as to obtain a proper distance between the front face of the adjusting shuttle 13 and the rear end of the shuttle 11, to the end that the electrical circuit will be certainly closed when the designating plate is struck; and yet that the circuit may not be closed by the vibration set up when a neighboring designating plate is struck. The action above described when the number 5 is struck by the bullet is similar to that of the number 4, number 3 and number 2. The shuttle 13 is not only capable of adjustment, but it also enables a prolonged electrical contact to be made by following up the front shuttle 11 on its return to battery.

Copies of this patent may be obtained for five cents each, by addressing the "Commissioner of Patents, Washington, D. C."

In Fig. 4 I show details of the method of 45 mounting one of the designating plates "P" on the bulkhead "E". This method is exceedingly simple as the designating plate "P" is securely bolted to the bent spring 6 by the bolts 16, and the bent spring 50 6 is substantially bolted to the bulkhead "E" by the through bolts 17.

While I have described my invention for use with the United States Army "A" target, I wish it distinctly understood that I 55 do not limit its use to the Army "A" target, as it is equally adaptable to every type of United States Army and Navy regulation small-arm targets, and variations of this principle may even be adaptable for 60 great gun targets. Furthermore, I wish it to be understood that I do not limit myself to the exact details of construction shown herein, as many minor changes suggest themselves without departing from the 65 scope of my invention.

Having thus described my invention and the method of its use, I claim:

A self scoring target consisting of an annunciator and a marking device in circuit 70 therewith, said marking device consisting of a series of bullet proof vanadium steel designating plates bent **S** shaped leaf springs, yieldingly supporting the same a steel shuttle board with insulated contact 75 making shuttles mounted therein for closing the electric circuit and actuating the annunciator when a portion of the target is hit, said **S** shaped springs being attached to the steel shuttle board substantially as 80 shown and described.

In witness whereof I hereunto set my hand.

MARK ST. CLAIR ELLIS.
